[57] CLAIM

The ornamental design for an “electrically powered waxer/polisher”, as shown and described.

DESCRIPTION

FIG. 1 is a perspective view of the eletrically powered waxer/polisher showing my new design;

FIG. 2 is a right side elevational view thereof;

FIG. 3 is a left side elevational view thereof;

FIG. 4 is a front elevational view thereof;

FIG. 5 is a rear elevational view thereof; and,

FIG. 6 is a top plan view thereof.

Broken lines in the figures are for illustrative purposes only and represent an environment in connection with which the invention is used, and the broken lines form no part of the claimed design.
